His Attorney.

UNITED STATES PATENT OFFICE

WILLARD E. PORTER, OF SWAMPSCOTT, MASSACHUSETTS, ASSIGNOR TO GENERAL ELECTRIC COMPANY, A CORPORATION OF NEW YORK

TIME SWITCH

Application filed January 22, 1931. Serial No. 510,490.

My invention relates to time switches and its object is to provide an improved time switch for general application which may be set with a high degree of accuracy and the 5 switch contacts of which may be operated by hand at any time without interfering with or disturbing the automatic setting. The energy for operating the switch automatically is obtained from the timing motor 10 and gradually stored in springs and released at the proper times, determined by the setting, for positive operation of the switch mechanism. In case the "on" or "off" time setting of the switch is advanced by 15 hand, such operation automatically winds the corresponding operating spring by an amount proportional to the advance in setting so that such operation never increases the burden of the timing motor or reduces 20 the energy available for automatic operation. These and other advantageous features, subsequently referred to, are combined in a time switch of compact, rugged construction.

The features of my invention which are 25 believed to be novel and patentable will be pointed out in the claims appended hereto. For a better understanding of my invention, reference is made in the following description to the accompanying drawings.

30 In Fig. 1 the essential parts of my time switch are represented in perspective in a somewhat less compact arrangement than that employed in its actual construction. Parts of the supporting structure and the 35 casing have been omitted. Fig. 2 is a detail view of one of the time setting dials.

The motor for establishing the timing function and supplying the energy for automatic operation is represented at 10 and in 40 this instance comprises a self-starting synchronous motor of a type extensively used for driving various timing devices when connected to an alternating current system of regulated frequency. 11 is a usual clock dial having hour and minute hands 12 and 13. These hands are driven from the synchronous motor through the usual gear train, not shown, and constitute a well known, highly reliable synchronous motor driven 45 clock. Other forms of clocks may be used

if provided with sufficient energy for operating the time switch mechanism now to be described.

The time switch mechanism is operated from the clock train through gears 14, 15, 55 16, 17 and 18. Gears 15 and 16 are secured together and in the design represented make one revolution in 12 hours in a clockwise direction. Gear 16 drives gears 17 and 18 in counter-clockwise directions one revolution 60 in 24 hours. Gear 16 is of sufficient length that gears 17 and 18 may be moved endwise in the operation of the time switch without breaking mesh with gear 16. To assist in the explanation of the invention, it may be 65 said that the time switch drive separates into two parts at gear 16, one part going to gear 17 and the other part to gear 18 and that these last-mentioned gears operate two mechanisms which are similar, one for performing the "on" function and the other for performing the "off" function of the device.

The switch member on which these two mechanisms operate is represented at 19 and in this instance comprises an insulated lever 75 pivoted at 20 and provided with a handle 21, extending toward the front, for manual operation, a contact arm 22 extending to the rear, and upwardly extending arms or pins 23 and 24 on opposite sides of the pivot point 80 20 by means of which the switch lever is automatically operated by the two time switch mechanisms controlled by gears 17 and 18 respectively.

The mechanism between gear 17 and operating pin 23 of the switch lever for performing the "on" function will now be explained. Gear 17 is secured to the forward end of a sleeve 25 free to rotate and slide endwise on a relatively stationary shaft 9. Secured to 90 the back end of this sleeve is a circular disc 26 and a hublike member 27 having a cam surface on its rear face. The slope of this cam surface is uniform and extends completely around the hub and the beginning and ends of the cam surface being connected by a step substantially parallel with the shaft 9. This cam cooperates with a relatively stationary cam 28 secured to shaft 9 adjacent its rear 95 end. The two cam surfaces are similar and 100

face each other and are held in contact by a compression spring 29 coiled about sleeve 25 between the disc 26 and the front plate 30 through which shaft 9 and sleeve 25 extend. The arrangement of the cams is such that as cam 27 is rotated in a counter-clockwise direction through sleeve 25 and gear 17, the sleeve assembly will be moved gradually endwise or axially toward the front over substantially a 24 hour period and at the end of such period the steps in the cam surfaces will come into alignment and spring 29 will suddenly force the sleeve member to the rear the length of the cam step.

It will be seen that during the substantially 24 hour period while the sleeve assembly is being forced toward the front, energy from the synchronous motor is being stored in spring 29 which resists the slow axial movement and this energy is suddenly released when the steps in the cam surfaces coincide. Use is made of this sudden axial movement and release of energy to move switch lever 19 from the "off" to the "on" position. This is accomplished through a U-shaped lever member comprising arms 31 and 32 both secured to a shaft 33. Arm 31 has its outer end turned up so as to be engaged as hereinafter described by the rear under surface of disc 26. The outer end of arm 32 contains a slot through which pin 23 of the switch lever 19 extends. This lever member is pivoted on the axis of shaft 33 so that when disc 26 suddenly moves to the rear it normally engages arm 31 and carries it, together with arm 32 and pin 23, to the rear. This rotates the switch member 19 about its pivot 20 from the "off" position shown to the "on" position where its switch contact 34 engages with stationary contact 35.

I have previously mentioned that the switch 19 may be operated manually in either direction at any time. In order that this may be accomplished means are provided for lowering the outer end of arm 31 so that it will pass freely beneath disc 26 without engagement therewith, when disc 26 is in any position to interfere otherwise with such free movement. The only exception to this occurs at the instant when disc 26 is suddenly carried to the rear in its automatic switch operating movement previously explained, at which time the arm 31 must of course be in the raised position. Switch lever 19 must also be free to move when the second automatic switch mechanism controlled by gear 18 operates and this is another reason for normally maintaining arm 31 in such a position that it will not engage disc 26 by reason of the movement of the switch lever 19. Arm 31 is pivoted in shaft 33 so that its outer end may be raised and lowered. A spring 36 maintains arm 31 raised against a stop lever 37 which lever is itself biased upward by reason of its light spring sup-

port 38 and when free to do so, rests lightly against the under side of disc 26. Fig. 1 shows the raised position of 31 and 37 and when thus positioned the upper outer end of arm 31 is in position to be engaged by disc 26 in its sudden backward axial movement. It will be noted that the upper rear surface of stop lever 37 is beveled at 39 so that as disc 26 moves to the rear and approaches the end or limit of such axial movement, it will depress stop lever 37 and with it arm 31 to a point where arm 31 may move beneath disc 26 without engagement therewith. The depressing of arm 31 does not occur however until the automatic switch operating movement performed thereby is completed. A catch lever 40 pivoted at 41 contains a notch positioned to engage the free end of stop lever 37 when in the depressed position to maintain it in such position as disc 26 gradually moves toward the front in the 24 hour period following an automatic operation. Catch lever 40 is biased toward its holding position by a light spring and is provided with a bent-over finger 42 at its top extending toward disc 26. As disc 26 approaches the limit of its axial movement toward the front, it engages finger 42 and moves lever 40 so as to release stop lever 37 and permit it to raise. Arm 31 is thus allowed to move upward again into operating position. The lateral position of disc 26 is now such that it is to the right or front of arm 31 for any position of switch lever 19 so that even though arm 31 is in the raised position the switch arm may be freely operated by hand or by the other automatic mechanism. The position of disc 26 just described is that illustrated in Fig. 1, catch lever 40 has released stop lever 37 and operating lever 31 is in the raised position. In a short period of time, assuming normal operation of the clock, the steps in the cam surfaces 27 and 28 will be in alignment and an automatic switch movement will occur. If, previous to such automatic operation, switch lever 19 should be moved to the "on" position by hand, it will remain in such position and the subsequent automatic movement of disc 26 to the rear will merely confirm such manual operation and depress and lock stop lever 37 and operating lever 31 in the lower inactive positions. From the above explanation it is seen that the switch lever is free to be operated by hand in either direction and may be left in any position without interference from the automatic control mechanism except at the instant the automatic function is performed and the operating means between the switch and automatic mechanism is connected only during, and in response to, an automatic operation.

This automatic operating function normally occurs once in a given period of time such as a 24 hour day when the steps in the

cam surfaces are in alignment. It can be made to occur at any time in such 24 hour period by rotatably adjusting the position of the normally stationary cam 28. This is done by turning shaft 9 by hand by means of a front thumb-piece 43 secured thereto. Shaft 9 is normally held from turning by a friction clutch having spring-pressed plates 44 secured to shaft 9 and embracing the rear frame plate 45 as the stationary part of the clutch. A closely graduated time dial 46 is secured to shaft 9 and cooperates with a stationary pointer 47 at the front of the device for the purpose of manually setting the mechanism for automatic operation at the desired predetermined time. The dial is of course graduated for 24 hours and divided into A. M. and P. M. halves. A more detail view of such a dial is shown in Fig. 2.

In making any substantial change in setting in the time of operation of the switch mechanism, the setting dial 43 should be rotated in a clockwise direction. The reasons for this are, first, that it is of course impossible to rotate cam 28 in a counter-clockwise direction past a point where the cam steps come together; second, the movements of the stop lever 37 and catch lever 40 in their action on operating lever 31 will be always the same as that previously described if in setting cam 28 the latter is turned in a clockwise direction; and third, the rotation of cam 28 in a clockwise direction supplements the action of the synchronous motor in storing energy in spring 29 since such manual operation results in moving sleeve 25 and the parts connected thereto forward to compress spring 29. To illustrate this point, let us assume the switch is set for operation at 2 A. M. and the clock indicates 3 A. M. For one hour the synchronous motor has been gradually storing energy in the spring 29 since the previous automatic operation and will continue to store energy at the same rate for the next 23 hours if the setting is not changed. However, let us assume that the switch is now reset manually for operation at 4 A. M. by turning dial 46 in a clockwise direction 22/24ths of a revolution. This manual operation compresses spring 29 exactly the same amount that it would be compressed by the synchronous motor operating over a 22 hour period so that during the one hour period from 3 A. M. to 4 A. M., following the manual setting just described until the automatic operation occurs, the synchronous motor does not have its load increased above normal, and moreover, when the automatic operation does occur, the spring contains the full amount of energy required for the automatic operation of the switch. For minor adjustments of the setting dial 46, it may be turned in either direction unless such adjustment is over a range where the cam steps meet, in which case dial 46 can only be adjusted in a clockwise direction and such adjustment will then cause the operation of the switching mechanism. If desired, the shaft 9 may be extended to the rear and the setting dial 46 and thumb nut 43 may be placed at the rear of the casing.

In order to maintain the proper relation between the time switch setting dial and the time as indicated by the clock hands, it is essential that in resetting the clock hands on any occasion the entire gear train between the clock hands and cam 27 be rotated a corresponding amount. In other words, cam 27 must be maintained in synchronous relation with the clock hands. If this is done the setting of cam 28 by dial 46 for a predetermined time of operation as indicated by dial 46 will always be correct. To provide for this a thumb nut 48 is secured to the minute hand shaft and when this thumb nut is turned to set the clock hands the time switch gear train is reset also. A suitable friction coupling, not shown, is contained between the synchronous motor and clock hand shaft to permit this setting and the time switch gear train is connected to the clock hand side of such friction clutch.

I have now described the construction and operation of that part of the mechanism for automatically moving the switch lever 19 from "off" to "on" position, together with the arrangement for permitting free movement of the switch lever and the setting of the mechanism to operate at a predetermined time. The mechanism for automatically moving the switch lever from "on" to "off" position and the related arrangement is similar to that already described except in a few details which will now be mentioned. This second mechanism is operated by gear 18 which rotates in the same direction and at the same rate as gear 17. The automatic movement of lever 32 connected to switch lever 19 through pin 24 is exactly the same as the automatic movement of lever 32 in its action on pin 23, but since pin 24 is on the opposite side of the pivot point 20 from pin 23, the movement of the switch lever 19 occasioned thereby is in the opposite direction or such as to move the switch from the "on" to the "off" position instead of from the "off" to the "on" position. The stop lever 37' and operating lever 31' are shown in the depressed or inactive positions and catch lever 40' is being moved to release but has as yet not released stop lever 37'.

Connected to rotate with gear 18 of the second mechanism is a cam disc 50 having two sections of different radius each extending half way around the disc. This cam operates an A. M. and P. M. semaphore lever 51 to indicate in an opening 52 in the clock dial. When the lower end of lever 51 rests against the lower portion of the cam, the upper end of the lever will indicate P. M. in the open-

ing 52. This assists in obtaining the correct relation between the clock hands and time switch gear train when the clock hands are set since the clock has a 12 hour dial and the 5 time switch a 24 hour dial. Thus, if the clock hands are set at 3:45 in the morning, and the semaphore should indicate P. M., it would be necessary to advance the clock hands and connected parts 12 hours in order 10 to bring the time switch mechanism into the proper relation. If this is done, then the semaphore will be operated by cam 50 to show A. M. in the opening 52 and the cams 27 and 27' will be rotated 180 degrees with 15 respect to their time setting cams. One can then rest assured that if he sets the time switch to go "on" at 8 A. M., it will function at that time, whereas, otherwise it might function either at 8 A. M. or 8 P. M.

20 In the illustration the clock indicates 7:45 A. M., the dial 46 is set for an "on" operation at 8 A. M., and the dial 46' is set for an "off" operation at 10 A. M. It can be seen from the relative positions of cams 27 and 27' with 25 respect to the stationary but relatively adjustable cams controlled by the setting of dials 46 and 46' that the switch mechanism is in proper synchronous relation with the clock hands. However when the time switch 30 is housed in a casing it may not be feasible to look at the cams and hence the semaphore is desirable.

Since an automatic operation of the switch immediately depresses the corresponding operating lever 31 or 31' and frees the switch lever, it is seen that theoretically there is no limit to the closeness at which the "on" and "off" settings may be made to each other except that both can not function automatically 40 at the same instant, since then one mechanism would oppose the other. However, it will be apparent that a very short "on" period or a very short "off" period may be had.

It will be noted that the switch contacts 34 45 comprise spring clips and cooperate with stationary blades 35 and 35'. The energy of spring 29 or the corresponding spring of the other mechanism is sufficient to positively close such circuit controller in either direction, making a firm wiping contact and because of the knife blade character of the switch it will be positively held in either circuit controlling position by its own spring friction until moved to some other position 50 either manually or automatically. As illustrated, stationary contact 35 comprises one terminal of the switch, and the movable contact 34 the other. The other contact 35' may also be used for controlling a different circuit 55 and other contact arrangements may be used as desired.

In the present embodiment of my time switch, I have represented two complete and similar mechanisms for operating the switch lever 19. It is seen that the construction

and function of each mechanism is complete in itself and that time switches may be built having one, two, or more such mechanisms operating upon one or more switch levers, as desired. 70

The time switch herein described has been built in forms adapted for controlling radio sets and for controlling electric ranges. The details of construction may differ somewhat, depending on the use for which the switch is intended, the nature of the circuit or circuits controlled, etc. I do not wish to limit my invention to immaterial details of construction, to any particular use, or to the number or nature of the circuit controlled, but seek 80 claims commensurate with the true spirit and scope of the invention disclosed.

What I claim as new and desire to secure by Letters Patent of the United States, is,—

1. A time switch comprising a member 85 mounted for rotational and axial movement, timing means for rotating said member at a uniform speed to make a revolution in a predetermined interval of time, cam means for gradually moving said member axially in one 90 direction a limited extent while it is being rotated over substantially a full revolution, means for resisting such axial movement and for suddenly moving said member axially in the opposite direction to the same extent at one 95 point in its revolution, a switch movable in opposite directions to different circuit controlling positions, operating means for said switch movable therewith and also movable to and from a position where it may be engaged 100 by said member in its sudden axial movement to move said switch in one direction, means responsive to the sudden axial movement of said member for moving said operating means to the disengaging position as the member approaches the limit of such axial movement, and means responsive to the slow axial movement of said member in the opposite direction for moving said operating 105 means to the engaging position as the member approaches the limit of such axial movement. 110

2. A time switch comprising a member mounted for rotational and axial movement, means for rotating said member at a uniform 115 speed to make a revolution in a predetermined interval of time, cam means for gradually moving said member axially in one direction while it is being rotated over substantially a full revolution, a spring for resisting such axial movement and for suddenly moving the member axially in the opposite direction at one point in such revolution, a pivoted switch lever movable in opposite directions to different circuit controlling positions, operating means for said switch lever movable to and from a position where it may be engaged by said member in its sudden axial movement to move said switch lever in one direction, and means actuated by the axial 120 movement to move said switch lever in the opposite direction. 125

movement of said member for moving said operating means to and from such engaging position whereby said switch lever is free to move to and from either of its circuit controlling positions without interference from said member except during the sudden axial movement thereof.

3. In a time switch, a shaft, a sleeve member rotatably and slidably mounted on said shaft, a timing motor for slowly rotating said sleeve member, a cam mechanism for slowly moving said sleeve member endwise in one direction as it is rotated over a substantial portion of a revolution, a spring 70 pressed by such endwise movement of the sleeve member, the cam mechanism having a step which permits a sudden movement of the sleeve member in the opposite direction by said spring at a predetermined point in its revolution, a pivoted switch lever movable in opposite directions to different circuit controlling positions, operating means for said switch lever movable to and from a position where it may be engaged by the sleeve member, the disengaged position permitting free manual movement of the switch lever in either direction and the engaged position permitting automatic movement of the switch lever in one direction by the sudden endwise movement of said sleeve member, and means controlled by the endwise movements of said sleeve for moving the operating means from the engaged to the disengaged position and vice versa.

35 4. A time switch comprising a member mounted for rotational and axial movement, means for rotating said member at a uniform speed to make a revolution in a predetermined interval of time, cam means for gradually moving said member axially in one direction while it is being rotated over substantially a complete revolution, a spring for resisting such movement and for suddenly moving said member axially in the opposite direction at one point in its revolution, means for adjusting the cam means for determining the point in the revolution of said member where the sudden axial movement will occur, a switch movable in opposite directions to different circuit controlling positions, operating means for said switch movable to and from a position where it may be engaged by said member in its sudden axial movement to move said switch in one direction, and means actuated by the axial movement of said member for moving said operating means to and from such engaging position whereby said switch is free to move to and from either of its circuit controlling positions without interference from said member except during the sudden axial movement thereof.

5. A time switch comprising a circuit controller movable in opposite directions to different circuit controlling positions, a clock, a pair of similar mechanisms driven by said

clock, one for automatically moving said circuit controller in one direction and the other for automatically moving said circuit controller in the opposite direction, said mechanisms being independently adjustable to perform their automatic operations at any different predetermined times in a given time interval, such as a day, normally disconnected operating means between said circuit controller and each of said mechanisms through which the automatic operations are performed, and means controlled by said mechanisms for respectively connecting the corresponding operating means only during the instant of automatic operation.

6. A time switch comprising a circuit controller movable in opposite directions to different circuit controlling positions, a clock, a pair of similar mechanisms driven by said clock, each mechanism including means for gradually storing energy from said clock and releasing it at a predetermined adjustable time in a given time interval, such as a day, for the automatic operation of said circuit controller, one mechanism operating the circuit controller in one direction and the other mechanism operating the circuit in the opposite direction, a normally disconnected operating means between said circuit controller and each mechanism, means controlled by the respective mechanisms for connecting its operating means only during the instant of its automatic operation, and manual means for operating said circuit controller in either direction independently of said mechanisms at all other times.

7. A time switch comprising a clock including a 12-hour clock dial, and hands therefor, a mechanism driven from said clock for performing an automatic switching operation at any predetermined adjustable time in a 24-hour day, a second mechanism driven by said clock for performing another automatic switching operation at any other predetermined time in a 24-hour day, separate dials graduated in divisions of a 24-hour day and in A. M. and P. M. for respectively adjusting the times at which the automatic switching operations will be performed by said mechanisms, means for simultaneously and synchronously setting the clock hands and the clock driven portions of the mechanisms, and means operated by one of the 24-hour mechanisms for indicating on the clock dial whether the clock hands indicate the A. M. or P. M. position of the automatic mechanism.

In witness whereof, I have hereunto set my hand this Twentieth day of January, 1931.

WILLARD E. PORTER.
